UNITED STATES PATENT OFFICE.

ORVILL H. SAWDY, OF IOLA, KANSAS.

CARPET-SWEEPER.

No. 833,343.

Specification of Letters Patent.

Patented Oct. 16, 1906.

Application filed March 15, 1906. Serial No. 306,254.

To all whom it may concern:

Be it known that I, ORVILL H. SAWDY, a citizen of the United States, residing at Iola, in the county of Allen and State of Kansas, have invented certain new and useful Improvements in Carpet-Sweepers; and I do declare the following to be a full, clear, and exact description of the invention, such as will enable others skilled in the art to which it applies to make and use the same.

This invention relates to improvements in carpet-sweepers.

The object of the invention is to provide a carpet-sweeper which will thoroughly sweep, brush up, and collect the dirt and dust from the floor or carpet.

The invention consists of certain novel features of construction, combination, and arrangement of parts, as will be hereinafter described and claimed.

In the accompanying drawings, Figure 1 is a side view of a carpet-sweeper constructed in accordance with the invention. Fig. 2 is a top plan view of the same. Fig. 3 is a horizontal sectional view through the casing, showing the interior part in plan. Fig. 4 is a transverse vertical sectional view.

Referring more particularly to the drawings, 1 denotes a box or casing in which is arranged a transversely-disposed axle or shaft 2, upon the outer ends of which are mounted supporting-wheels 3. The sides of the box or casing 1 are provided with rearwardly-projecting extensions 4, having arranged therein a transversely-disposed shaft 5, on which are mounted rear supporting wheels or rollers 6.

In the lower forward portion of the box or casing 1 is arranged a dust or dirt pan 7. Immediately in rear of the pan 7 is arranged a transversely-disposed rotary brush 8, on the shaft 9 of which, adjacent to each end of the same, are mounted balance or fly wheels 10. The ends of the shaft 9 of the brush 8 project through the sides of the box or casing and have mounted thereon friction-wheels 12, which are adapted to be frictionally engaged by the supporting-wheels 3, whereby motion is imparted to the brush 8. The ends of the shaft 9 are journaled in a bar or strap 13, which passes around the forward end and sides of the casing to which it is secured, the side portions of the strap being spaced from the sides of the casing 1, as shown.

The ends of the axle or shaft 2 of the supporting and drive wheels 3 pass through slots in the sides of the casing and are journaled in

elongated bearings 13' in the bar or strap 13, as shown, so that when the machine is pushed in a forward direction the wheels 3 will be brought into frictional engagement with the wheels 12 on the rotary brush-shaft 9; thereby imparting motion to the same. At the end of each forward stroke or each time the machine is stopped there will naturally be a slight rearward movement or jerk, which will throw the supporting-wheel 3 forward; thereby disengaging the same from the friction-wheels 12, which being thus released will permit the shaft 9 and brush 8 to continue to revolve a greater or less number of turns, owing to the momentum or power stored up by the fly-wheels 10 on the shaft 9, as will be understood, thereby taking up thoroughly all dirt gathered by the non-rotary brush 16, hereinafter described.

Secured to the rear extensions 4 of the box or casing 1 are inwardly-projecting vertically-disposed guides 14, which are adapted to engage recesses 15, formed in the ends of a brush or broom 16, which is arranged between said extensions 4. By this arrangement the brush 16 is adapted to have a vertical sliding movement between said extensions. Coil-springs 17 are arranged upon the top of the box or casing 1, one end of said springs being connected to the top of the brush 16, whereby the same is normally lifted and held in a raised position out of engagement with the surfaces on which the sweeper is resting. Suitable stops 18, which are secured to the guides 14, are arranged to prevent the brush from being lifted too high by the springs 17. Pivotaly connected to the top of the brush 16, by means of apertured lugs 19, is a handle-bail 20, having arranged thereon a socket to receive a handle 21, by which the machine is pushed.

When the machine is pushed forwardly by the handle 21, the brush 16 will be forced downwardly into engagement with the carpet or surface being swept, which will brush or sweep the dirt ahead, where it will be taken up by the rotary brush 8 and deposited into the pan 7, thus thoroughly cleaning the surfaces over which the machine is being passed. As soon as the machine is stopped and the pressure removed from the handle 21 the spring 17 will lift the brush from said surface, so that the machine may be readily drawn backward.

From the foregoing description, taken in connection with the accompanying drawings,

the construction and operation of the invention will be readily understood without requiring a more extended explanation.

Having thus described my invention, what I claim as new, and desire to secure by Letters Patent, is—

1. In a carpet-sweeper, the combination with a wheeled box or casing, of a dust-pan arranged therein, a rotary brush revolvably mounted in said casing, means whereby said brush is revolved, a non-rotary brush carried by said casing, guides arranged on said casing to engage guideways or recesses formed in said brush whereby the same has a vertical sliding connection with said casing, springs connected to said casing and to said brush whereby the latter will be lifted and held in an inoperative position, and a handle pivotally connected with said brush whereby the same is forced downwardly into working position and whereby the machine is pushed along, substantially as described.
2. In a carpet-sweeper, the combination with a box or casing having front supporting-wheels and rear supporting-rollers, of a rotary brush mounted therein, friction-wheels arranged on the shaft of said brush to be engaged by said front supporting-wheels and thereby revolve said brush, fly-wheels arranged on the shaft of the latter, a non-rotary brush, means whereby the same is slidably mounted in said casing, springs to normally elevate said brush, stops to limit the upward movement of the same, and a handle pivotally connected to the brush whereby the latter is forced to a working position and the machine pushed along, substantially as described.
3. In a carpet-sweeper, the combination

with a box or casing, having front, driving and supporting wheels and rear supporting-rollers, of a rotary brush journaled therein, friction-wheels mounted on the shaft of said rotary brush, means whereby said front driving-wheels are frictionally engaged with and disengaged from said friction-wheels, a non-rotary brush slidably mounted in said frame or casing, means whereby said brush is lifted and held up in an inoperative position, and a handle connected to said brush whereby the latter is forced downwardly to a working position and the machine pushed forwardly, substantially as described.

4. In a carpet-sweeper, the combination with a box or casing having front driving and supporting wheels and rear supporting-rollers, of a rotary brush revolvably mounted in said casing, friction-wheels and fly-wheels mounted on the shaft of said rotary brush, a bar or strap having bearings for the shafts of said front drive-wheels and said rotary brush, the bearings of said drive-wheels being elongated, whereby the latter are engaged with and disengaged from said friction-wheels, a non-rotary brush slidably mounted in said casing, springs to lift and hold said brush up in an inoperative position, and a handle connected to said brush whereby the latter is forced downwardly to an operative position and the machine pushed forwardly, substantially as described.

In testimony whereof I have hereunto set my hand in presence of two subscribing witnesses.

ORVILL H. SAWDY.
